UNITED STATES PATENT OFFICE.

ROBERT L. CLARK, OF UNION, WEST VIRGINIA.

COAL-HOD.

1,217,706.

Specification of Letters Patent. Patented Feb. 27, 1917.

Application filed March 15, 1916. Serial No. 84,336.

To all whom it may concern:

Be it known that I, ROBERT L. CLARK, a citizen of the United States, and a resident of Union, in the county of Monroe and State 5 of West Virginia, have invented a new and Improved Coal-Hod, of which the following is a full, clear, and exact description.

The general object of my invention is to provide a coal hod equipped with a guard attachment arranged to be moved to a position 10 above the upper edge of the hod to prevent the spilling of coal over the sides of the hod when discharging the coal directly from the hod into a stove, furnace, or the like.

13 More particular objects of the invention are to provide a guard of the indicated character having a handle movable with the guard to a position to be available in assisting in the proper holding and convenient 20 manipulation of the hod to discharge the coal; and to provide a device of the indicated character having strength and simplicity and which may be readily attached to coal hods of conventional form.

25 The invention will be particularly explained in the specific description following.

Reference is to be had to the accompanying drawings forming a part of this specification in which similar reference characters 30 indicate corresponding parts in all the views.

Figure 1 is a perspective view of a coal hod provided with my improved guard;

Fig. 2 is a longitudinal vertical section showing the hod and guard in position for 35 discharging coal.

The body 10 of the hod may have the conventional form of such articles including the discharge spout 10^a and having the usual bail 11.

40 My improved guard 12 is curved in horizontal section to conform to the rounding body of the hod 10, and at the front the said guard is given the form of side arms 13 extending upwardly and forwardly and terminating at the spout 10^a with the upper edges of the arms 13 projecting above the sides of said spout. In order to so attach the guard 12 as to permit the same to be lowered to a position below the top of the 45 hod or to be rocked upwardly and forwardly to the guard position, a slot and pin connection is established between the arms 13 and the spout 10^a, there being a slot 14 in each arm and a pin 15 on the spout extending 50 through the said slot.

Similarly, at the back of the hod there is a

slot and pin connection, there being a vertical slot 16 in the guard 12 and a pin 17 on the hod and extending through said slot.

At the back of the guard 12 below the slot 60 16, said guard is provided with a handle 18 to be gripped by one hand of the user while the other hand takes hold of the bail 11.

By the described construction, it will be seen that when the coal is to be discharged, 65 by tilting the hod sufficiently as indicated in Fig. 2, the user, by gripping the handle 18 and bail 11, first swings the guard upwardly and forwardly so that the said guard projects a gradually increasing distance from 70 the front of the spout 10^a to the back of the hod. The handle 18, at this time, serves to assist in lifting the hod and in the proper manipulation of the same to discharge the coal, the discharge being effected without 75 any spilling of the coal over the sides of the hod.

Having thus described my invention I claim as new and desire to secure by Letters 80 Patent:

1. A coal hod formed with a spout and provided with a bail, and a guard extending at the back of the hod and curved in cross section to conform to the curvature of the hod, said guard presenting side arms extending forwardly and upwardly and connected with the sides of the spout by slot and pin connections, said arms projecting above the spout, and said guard having a slot and pin connection with the hod at the back 90 and being provided with a handle below the last-mentioned slot and pin connection.

2. The combination with a coal hod having a bail, of a guard extending around the back of the hod and provided with forwardly extending arms, pivotally connected with the hod at the front, the said guard having a handle at the back to rock said guard and coact with the bail in lifting and manipulating the same to discharge its contents, and 100 the said guard having a sliding connection with the hod at the back of the latter.

3. The combination with a coal hod having a bail formed with a discharge spout, of a guard presenting side arms extending forwardly and upwardly and pivotally secured to the said spout at the sides thereof, the upper edge of the said arms projecting above the spout, the said guard extending around the back of the hod and being movable on 110 the said pivotal connections to a position to lie below the hod at the back of the latter

or to a raised position projecting to a gradually increasing extent from the front ends of the side arms at the spout around the back of the hod, there being co-acting means on the hod and guard at the back to limit the rocking movement of the guard in both directions.

In testimony whereof I have signed my name to this specification in the presence of two subscribing witnesses.

ROBERT L. CLARK.
